UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER FOLDING BOX.

Application filed November 24, 1923. Serial No. 676,693.

To all whom it may concern:

Be it known that I, SAMUEL BERGSTEIN, a citizen of the United States, residing at Middletown, in the county of Butler and State 5 of Ohio, have invented certain new and useful Improvements in Paper Folding Boxes and the like, of which the following is a specification, reference being had therein to the accompanying drawings.

10 This invention relates to paper folding boxes, having particular reference to counter or show window boxes for displaying confections, toilet articles, etc.

15 The main object of the invention is to provide a paper folding box of the character referred to which will be adapted to be made in one piece, thus to effect substantial saving of material in the cutting of the blanks from which the boxes are made, and also to 20 minimize time and labor production costs.

25 A further object is to provide a box upon which suitable advertisements can be printed, including an advertisement on a display flap as the box is adjusted for counter or show window display, in a single printing operation, thus to further reduce the cost of production.

30 An object of the invention is to provide a box which, as furnished to the trade in knocked-down form will be cut and scored and pasted ready to be set up, certain of the 35 cut portions being only partially severed for the purpose of retaining the coacting portions in normal relation one with another as the boxes are handled in stock, the uncut or retaining connections being of such slight extent that parting of the portions so joined together can be easily effected by applying slight pressure thereto as the boxes are 40 set up.

45 While the improved box, as herein shown in complete form, is adapted as a display box, the box in a modified form is also adapted as a container for articles, as shoes, hardware, accessories, etc., not ordinarily displayed in boxes, the object attained in the modification consisting in a one-piece box, of novel construction, in which the opposite sections of the box—lid and body— 50 are joined together, thus serving to keep the box intact at times when the contents are temporarily removed from the box.

In the accompanying drawings the im-

proved box is illustrated in the two forms referred to, in which:

55 Fig. 1 illustrates the paper blank for making the display box, the blank being shown flat, slotted and scored for folding and setting-up;

Fig. 2 is a plan view illustrating the 60 blank shown in Fig. 1 folded in knocked-down form;

Fig. 3 is a side elevation of the box closed;

Fig. 4 is an elevation of an end of the 65 box closed;

Fig. 5 is a plan view of the box closed;

Fig. 6 is a side elevation of the box set-up for displaying its contents;

Fig. 7 is an end view of the box as shown in Fig. 6;

Fig. 8 is a bottom view of the box as shown in Fig. 6.

The paper blank for the box, as shown in Fig. 1, consists of one piece comprising the opposite sections A and B adapted respectively to form the body and the lid of the box, the opposite ends of the blank being cut and scored in a well known manner to be folded and glued one part to another as the box is formed; the corner flaps 1—2 being 70 adapted to be folded inwardly and glued to the inner surfaces of the end flaps —3, a compound fold being made of the ends of the blank, in knocked down form, on score lines 5, as shown at 4 in Fig. 2.

75 To set-up and close the box the blank is folded upwardly on score line —6, the top section B being then folded over section A on score line 7, the sections A and B being brought together telescopically with the intermediate portion 8 forming an end of the box, the closed box being illustrated in Figs. 3, 4 and 5, the end flaps 9 being folded over the end of the box outside the portion 8, as shown in Fig. 4, and joined one to the other 80 by means of oppositely arranged notches 10. In the closed box the side portions 11 are outside, as shown in Fig. 3, the same being held intact with the main portion B by uncut portions —a which serve to unite one 85 portion with another.

90 As best shown in Fig. 1 the paper blank for the display box is provided with the flap C suitable for having an advertisement printed on the outside thereof relative to 100 the contents of the box, the flap being held

5 intact with the main portion B by means of uncut portions —a until the box is set-up to display its contents when the connecting portions —a will be broken to release the flap which is then folded upwardly on score line 7 and downwardly on score line —13, as shown in Fig. 6, with the edges 14 of the flap engaging seats 16 formed in the intermediate end portion 8, the lip 15 intermediate the edges 14 of flap C serving as a projection to be engaged by thumb and finger to raise the flap and break the retaining connections —a which unite the flap with portion B. As herein stated any advertisement printed on flap C will be on the outer surface of the box blank and can thus be printed on the same operation with other advertisements printed on the body of the box.

20 As further shown in Figs. 6, 7 and 8, the lid portion of the display box as set-up is formed into a rectangular-shaped pedestal —D, adapted to support the box at a suitable angle for displaying its contents, the 25 rectangular shape of the pedestal being effected by breaking the connections —a which unite side portions 11 with portion B and then folding the portions 11 inwardly at right angles and connecting one portion 30 with the other by means of opposite slots 17, as best shown in Fig. 8, the open box and the pedestal being connected one to the other by the strip portions 18, a lip —19 formed in the bottom of portion A serving 35 to hold the parts in assembled relation by being brought into engagement with the upper edges of portions 11.

For the non-display type of box, the advertisement flap —C is not cut from portion 40 B, portions 11 also remaining uncut from portion B and the lips 15, 16 and 19 omitted, the box in other respects being substantially the same as that herein described.

45 Having described my invention, I claim:
1. A paper folding box formed of an integral blank slotted and scored for folding and including opposite portions adapted to form the top and bottom of the box respectively, joined one to the other by an intermediate portion adapted to form an end

55 of the box, slotted side portions outwardly adjacent said intermediate portions one slot being inverse to the other and adapted to overlap and to be joined one to the other outwardly of said intermediate portion, as the box is set up, by means of said slots.

2. A paper folding box formed of an integral blank including opposite portions adapted to form the top and bottom of the box, opposite side portions partially cut 60 from said top portion of the blank and adapted to be turned inwardly transversely of the blank, one portion overlapping the other, to form, together with an end and remaining side portions of the top of the box, a base adapted to be folded under an end of the box whereby to present the same at a suitable angle for displaying the contents thereof.

3. A paper folding box formed of an integral blank including opposite portions adapted to form the top and bottom of the box, slotted portions partially cut from the opposite sides of said top portion of the blank and adapted to be turned inwardly 65 transversely of the blank and joined one to the other by means of said slots therein whereby to form, together with an end and remaining side portions of the top of the box, a base adapted to be folded under an end of the box whereby to present the same at a suitable angle for displaying the contents thereof.

4. A paper folding box formed of an integral blank including opposite portions adapted to form the top and bottom of the box, a portion partially cut from said top portion suitable for displaying an advertisement thereon as the box is set up, portions cut from the opposite sides of the top portion 70 and adapted together with the end remaining side portions to form a base for the box whereby to support the same at an angle, intermediate portions between said display and said side portions adapted to be folded 75 relative to said base as the same is brought to position under the box.

In testimony whereof, I affix my signature.

SAMUEL BERGSTEIN.
